(57) **CLAIM**

The ornamental design for a tripod for camera, as shown and described.

DESCRIPTION

FIG. 1 is a front, left, and bottom perspective view of a tripod for camera in a closed configuration, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front, left, and top perspective view of a tripod for camera in an alternate open configuration.

The broken lines shown in drawings illustrate portions of the tripod for camera that form no part of the claimed design. The dot-dash lines in the figures represent the boundaries of the claim and form no part of the claimed design.

1 Claim, 5 Drawing Sheets
